UNITED STATES PATENT OFFICE.

EDWARD WOOLLEY, OF WOONSOCKET, RHODE ISLAND.

THREAD-CLEARING DEVICE.

1,040,087.

Specification of Letters Patent.

Patented Oct. 1, 1912.

Application filed December 7, 1910. Serial No. 596,040.

To all whom it may concern:

Be it known that I, EDWARD WOOLLEY, a citizen of the United States, and a resident of the city of Woonsocket, in the county of 5 Providence and State of Rhode Island, have invented certain new and useful Improvements in Thread-Clearing Devices, of which the following is a specification.

The invention relates to devices designed 10 for the purpose of clearing or cleaning silk filaments or threads, or cotton or woolen threads and yarns by removing therefrom slubs, knots, and unusually thick portions before the same are woven.

15 The improvements as applied by me, form a part of the winder and consist of an attachment or fixed part located between the reels or "swifts" and the bobbins in the said machine, so that the thread when 20 wound upon the bobbin will be free from such imperfections and may be woven into fabric of the finest quality without further treatment or inspection.

25 The principal objects of the improvement are to provide a clearing device of simple and convenient construction, and reliable and efficient operation, which may be used without alteration and with merely a simple adjustment for the clearing of threads and 30 yarns of any size, from the finest silk filament to the coarsest yarns, and will act with equal efficiency and reliability in all cases.

35 The improvements consist in the construction, combination and arrangement of parts hereinafter described and claimed and illustrated in the accompanying drawings.

In the said drawings, Figure 1 is a perspective view of a thread cleaning device 40 embodying the improvements. Fig. 2 is a plan of the reverse side. Fig. 3 is an edge view of the same. Fig. 4 is a vertical cross-section on the line 4-4 of Fig. 3 looking in the direction indicated by the arrows. Fig. 45 5 is a vertical section of a pair of the plates with beveled edges which form the tapering slots.

In describing the invention, it will be referred to in connection with its use for 50 cleaning or clearing textile yarns as this was the first use to which the device was put, and, inasmuch as the principal imperfections found are what are known as "slubs," this term will be used generically to indicate all imperfections.

In the weaving or knitting of fabrics it is,

of course, desirable to have the thread employed of uniform thickness and free from all imperfections, especially slubs or bunches of fiber, for the reason that the value of the 60 fabric is greatly deteriorated by the presence of these imperfections. A few slubs in a piece of cloth or knitted fabric will sometimes make it a "second" and compel the manufacturer to sell it at a loss, or have his 65 business reputation suffer, not only for the reason that these imperfections affect the appearance of the cloth but because they sometimes cause threads to pull out, thus leaving flaws in the material, while it is 70 being worked or worn. It will be appreciated, therefore, that any device which will effectively and reliably prevent these imperfections is of great value and importance to 75 the textile industry.

The plate A is adapted to be secured to the winder in any desired manner between the reels and the bobbins so that the thread in passing from the hanks to the said bobbins will pass through the slots of the plate. 80 In Fig. 1 the plate is shown as it is adapted to be arranged in a winder in which the bobbins are above the reels and in this case the travel of the thread is upward. In machines in which the bobbins are below the 85 reels—and this is perhaps the more usual modern construction—the plate is inverted so that the thread in traveling downward through it will pass through the plate in the same manner.

90 The plate A is provided with a series of open ended slots B running from one edge to a point near the opposite edge, and on both sides of each of these slots are a pair of plates C with horizontally beveled opposite edges so that when they are placed together a tapering slot D is formed within the slot B of the plate A. These plates C are secured to the main plate by means of machine screws C', or in any other suitable 95 manner and may be readily attached thereto and detached therefrom when desired.

Attached to the plate A on the same side as the plate C and running across the slots therein at right angles thereto is an adjusting bar E which is adapted to be moved back and forth over the plate and held at any desired point in the following manner. The plate A is provided with a diagonal slot F near each end, the two slots being parallel, and receiving grooved pins G, G', the former being fixed to the bar E near one end 105 110

and having its groove engaged by the edges of the slot, and the latter being similarly fixed and arranged, but extending on the opposite side of the plate A and having a 5 screw-threaded aperture in this part at right angles to its longitudinal axis. This threaded aperture is adapted to receive the screw bolt H passing through the stud A² on one end of the plate A and provided with a 10 flanged head H' and a fixed collar H², which prevent it from having anything but rotary movement therein. The adjustment of the bar E is therefore accomplished by simply rotating the screw-bolt H and thus causing 15 the pin F' to move back and forth in the slot carrying with it the said bar.

It will be apparent that if the slots were not provided with means for preventing the threads from working inward the said 20 threads would inevitably become wedged therein and break, and it is for the purpose of causing the thread to pass through the slot at the point where the width of the slot corresponds with the diameter of the thread 25 that the adjustable bar E is provided. The thread is therefore caused to pass through suitable guides above and below the bar so that it will have a tendency to work toward the inner end of the slot, and the interposition 30 of the bar E checks this tendency and at the same time by exerting a slight pressure on the thread causes it to remain in that portion of the slot which is crossed by the outer edge of the bar. In this manner the 35 position of the thread relative to the slot may be accurately adjusted and the thread caused to pass through the portion of the slot which barely allows it clearance and which will not permit any slubs on the thread to pass.

40 In operation the bar E is adjusted so that its outer edge crosses the slots at a point where the width of the said slots corresponds with the diameter of the threads to be wound, and the threads then in passing 45 through the slots press slightly against the bar so that they are constantly in the narrowest portion of the slots to which they have access. When therefore, a slab attempts to pass it will be caught by the edges 50 of the plates and the travel of the threads through the slots thus checked. This will attract the attention of the operator who will remove the slab, piece the thread, if necessary, and start that portion of the machine 55 in operation again.

It will be seen that by the use of this device threads or yarns of various widths may be cleaned or cleared, and that the slab catching slots may all be adjusted by one 60 simple movement of the guiding bar. It

will also be apparent that the winding operation may proceed without interruption as to all the threads except the one being cleared, when a slab is caught, and that the removal of imperfections from the thread 65 or yarn is accomplished by means of this device in a most expeditious manner and without danger and causing knots or tangles.

What I claim is:—

1. In a device of the character described 70 the combination of a plate provided with a plurality of tapering slots and a bar extending across said slots and adjustable longitudinally with respect thereto, said adjustment of the bar comprising a connection between the plate and the bar, and a set-screw for holding the said bar in various positions. 75

2. In a device of the character described 80 the combination of a plate, a series of openings therein extending from one edge of the plate into its interior, a pair of plates secured to the first named plate adjacent to each opening and partly closing the same, said plates having beveled edges converging inwardly to form a tapering slot. 85

3. In a device of the character described 90 the combination of a plate, a series of openings therein extending from one edge of the plate into its interior, a pair of plates secured to the first named plate adjacent to each opening and partly closing the same, said plates having beveled edges converging inwardly to form a tapering slot, and a bar movable with respect to and extending across the said slots. 95

4. In a device of the character described 100 the combination of a plate adapted to be suitably mounted, provided with a series of openings therein extending inwardly from one edge thereof and substantially parallel 105 with each other, a plurality of plates at the edge of each opening, said plates having beveled edges forming a tapering slot within the opening of the plate, and a bar extending across said slots, a screw-bolt mounted in the first named plate, a pin secured to the bar and receiving said screw bolt, a diagonal slot in the said plate through which said pin extends, the construction and arrangement being such that the rotation of the screw-bolt causes the pin to travel along said diagonal slot and impart movement to the bar longitudinally of the said tapering slots. 110

Witness my hand this 18th day of November, 1910, at the city of New York, in the 115 county and State of New York.

EDWARD WOOLLEY.
